(57) **CLAIM**

We claim the ornamental design for an inflatable raft with underwater viewing window, as shown and described.

DESCRIPTION

FIG. 1 is perspective view of an inflatable raft with underwater viewing window according to the present invention; FIG. 2 is a left-side view thereof;

FIG. 3 is a right-side view thereof;

FIG. 4 is a top view thereof;

FIG. 5 is a bottom thereof;

FIG. 6 is a front view thereof; and,

FIG. 7 is a rear view thereof.

Filling valves are shown in broken lines throughout the figures, and form no part of the patented design. Bottom surface features are shown in broken lines in FIG. 5, and form no part of the patented design.

1 Claim, 5 Drawing Sheets
